UNITED STATES PATENT OFFICE.

ALBERT COWELL, OF KIDDERMINSTER, ENGLAND.

DESIGN FOR A CARPET-PATTERN.

Specification forming part of Design No. 5,887, dated June 4, 1872.

To all whom it may concern:

Be it known that I, ALBERT COWELL, of Kidderminster, Worcestershire, in England, have invented a new and original Design for Carpets; and I do hereby declare that the following is a full, clear, and exact description thereof, which will enable others skilled in the art to make and use the same, reference being had to the accompanying photographic illustration forming part of the specification.

The nature of my invention is fully represented in the accompanying photographic illustration, to which reference is made.

This invention relates to a new carpet design, in which two main figures—one in shape of a cross, the other with nearly circular outline—are arranged on a richly ornamented background. The cross-shaped figure contains a bouquet of flowers in the center, said bouquet being on a dark ground, which has bulbous protuberances, as shown. The lighter border of this figure has a fancifully-shaped outline, and contains smaller crosses in its arms, and small squares in its inner angles. The other figure has an ornamental four-armed center, with trefoil tufts at the extremities. The dark ground of this figure has bulbous protuberances, like the other, and the extreme outline is also shaped in the style of the outline of the cross-shaped figure.

I claim as my invention—

The design for carpets, as shown.

ALBERT COWELL.
